(57) **CLAIM**

The ornamental design for an electric knife blade, as shown and described.

DESCRIPTION

FIG. 1 is a perspective view of an electric knife blade showing our new design;

FIG. 2 is a top plan view of FIG. 1;

FIG. 3 is a right side elevation of the blade of FIG. 1;

FIG. 4 is a bottom plan view of the blade of FIG. 1;

FIG. 5 is a left side elevation;

FIG. 6 is a rear elevation view thereof;

FIG. 7 is a front elevation view thereof;

FIG. 8 illustrates the right side elevation, the inner, or inside, surface of the left hand blade as seen in FIG. 1; and,

FIG. 9 illustrates the right side elevation, the inner, or inside, surface of the right hand blade as seen in FIG. 1.
